ATOMIZER HEAD

Marcel Franck, New York, N. Y.

Application June 18, 1951, Serial No. 15,596

Term of patent 7 years

(Cl. D83—1)

To all whom it may concern:

Be it known that I, Marcel Franck, a citizen of the Republic of France, residing at New York city, in the county of New York and State of New York, have invented a new, original, and ornamental Design for an Atomizer Head, of which the following is a specification, reference being had to the accompanying drawing, forming part thereof.

In the drawing:

Fig. 1 is a front elevational view of an atomizer head, showing my new design;
Fig. 2 is a rear elevational view thereof;
Fig. 3 is a side elevational view;
Fig. 4 is a top plan view;
Fig. 5 is a bottom plan view; and
Fig. 6 is a sectional view on line 6—6 of Fig. 2, showing the shape of the grooves on the rear face of the main body portion of the atomizer head.

I claim:

The ornamental design for an atomizer head, substantially as shown.

MARCEL FRANCK.
